UNITED STATES PATENT OFFICE.

FRANK KUHN AND FRANK E. SHAILOR, OF DETROIT, MICHIGAN; SAID SHAILOR
ASSIGNOR TO SAID KUHN.

DESIGN FOR AN ELECTRIC PERCOLATOR.

47,465.

Specification for Design.

Patented June 15, 1915.

Application filed April 1, 1915. Serial No. 18,605. Term of patent 14 years.

To all whom it may concern:

Be it known that we, FRANK KUHN and FRANK E. SHAILOR, both citizens of the United States of America, residing at Detroit, in the county of Wayne and State of Michigan, have invented a certain new, original, and ornamental Design for Electric Percolators, of which the following is a specification, reference being had therein to the accompanying drawings, forming part thereof, in which the figure represents a

percolator in side elevation, illustrating our invention.

We claim:

The ornamental design for an electric percolator, substantially as shown.

FRANK KUHN.
FRANK E. SHAILOR.
